LIGHTING DEVICE

André Claude, Nanterre, France, assignor to Société Anonyme pour les Applications de l'Électricité et des Gaz Rares, Etablissements Claude Paz & Silva, a corporation of France

Application August 26, 1936, Serial No. 97,980
In Great Britain August 29, 1935

4 Claims. (Cl. 240—1.1)

It is known to employ combinations of luminous tubes for lighting. One of these combinations is formed of neon tubes and mercury tubes, the walls of which are of transparent glass, the 5 brilliancy of the latter tubes being several times greater than that of the neon tube.

The spectrum of the light emitted by this combination of two tubes consists entirely of lines 10 and consequently does not render all colors perfectly. For this reason, it is preferable to replace the mercury tubes by tubes of which the inner wall contains or is coated with fluorescent substances. Such tubes have a much greater luminous efficiency than that of the usual mercury tubes and the spectrum of the light emitted 15 by them has a continuous background which appreciably improves the light resulting from their combination with neon tubes.

This mixing of the colors is only perfectly 20 cautious if, when looking in the direction of the two tubes, the mercury fluorescent tube, when it is a diffuse light tube, is placed behind the neon tube which is transparent. In the opposite direction, however, the said fluorescent tube 25 intercepts the light emitted by the neon tube and the light obtained is colored. It is the same if the fluorescent tube is transparent, for example made of glass containing a uranium salt, and the neon tube is a diffuse light tube, for example, 30 one made of opal glass.

The object of the present invention is to provide a source of light employing combinations 35 of fluorescent tubes with other tubes, such that radiations of different colors are mixed sufficiently to avoid undesired colored effects.

The invention comprises disposing the tubes of the combination in a common light-dispersing envelope and separating them sufficiently in such a manner as to obtain the desired luminous effect, and to provide means to suppress or to 40 limit relatively to the area of the envelope the zone of color effect produced thereon by the absorption by the diffused light tube of light rays received by it from the transparent tube, these 45 means being designed to operate without sensibly diminishing the luminous flux traversing the entire envelope.

One of these means comprises placing the two tubes in a diffusing envelope of substantially 50 greater diameter than the sum of the diameters of the tubes, and for example equal to at least twice the minimum space occupied by the tubes, and spacing the tubes sufficiently from the envelope in order to obtain the desired luminous 55 effect.

Another means comprises disposing in the interior or on the exterior of the envelope on the wall nearest the diffused light tube, an opaque reflecting band for preventing the exit of the light emitted by the diffuse light tube and sending back the said light to be mixed with that of the transparent tube. The said band is arranged to mask the whole or the greater part of the area of the envelope wall defined by the intersection with said wall of the shadow cone 10 thrown by the diffused light tube impinged upon by light rays from the transparent tube. The width of the said reflecting band may be for example equal to the diameter of the fluorescent tube.

In certain cases, these two means may be employed simultaneously.

In the accompanying drawing, which is intended to illustrate the invention of the application by way of example:

Figure 1 is a diagrammatic view showing the arrangement of the luminous tubes in a common cylindrical envelope, taken in section at right angles to the axis of the envelope.

Figure 2 is a view similar to Fig. 1 of a modification.

Figure 3 is an elevation, partly in section, of a complete lamp according to the invention.

Figure 4 is a section of Fig. 3 taken on line 4—4.

In Figure 1, 1 designates the cylindrical envelope for dispersing the light, 2 a luminous tube emitting diffused light, and 3 a transparent light-emitting tube. It will be seen that, owing to the arrangement of tubes 2 and 3 in the envelope, the tube 2 will absorb the major part of the light rays issuing from the tube 3, the part A, B of the envelope emitting almost exclusively right from the tube 2. On the contrary, the part A, C, B of the wall will furnish a substantially uniform light formed by mixture of the radiations emitted by the tubes 2 and 3. It will be seen that if the diameter of the envelope is increased, the length of the part A, B intersected on this wall by the shadow cone thrown by the tube 2, will increase less rapidly than the diameter of the envelope, whereby the relative importance of the radiation from the portion A, B of the wall is thus diminished. Hence, by a suitable choice of the diameter of the envelope, the effect of this portion A, B can be made negligible.

In the modification shown in Fig. 2, the color effect of the area A, B is suppressed by arranging at this region an opaque reflecting band 45

preventing any direct translation of light from the part A, B, and reflecting the light rays which arrive thereon from the tube 2. At the same time, the rays, which arrive from the tube 3 by reflection on the interior wall of the envelope 1, will effect mixture of these rays.

In the construction shown in Figs. 3 and 4, 1 denotes the cylindrical envelope, 2 the diffused light tube, and 3 the transparent tube, as before. 10 4 designates the opaque reflecting band. 5 and 6 are the ends of the tubes 2 and 3 each containing an electrode, said ends being enclosed in an opaque casing 7. The other electrodes are arranged symmetrically with respect to the said 15 electrodes 5, 6 in another opaque casing 8.

It has been found that the luminous flux emitted by the group of tubes through the envelope is not very appreciably less than that emitted by a similar group of bare tubes if the envelope 20 is made of a composite glass comprising at least one layer of opal glass, the thickness of which is of the order of several tenths of a millimeter. This layer may be surrounded for example by one or more layers of transparent glass. The 25 envelope or external tube is suspended for example from the ceiling of the room to be illuminated and it may carry a reflecting band, such as is shown at 4 in the drawing, on the wall nearest the ceiling, the diffuse light tube, for 30 example the fluorescent tube 2 containing a deposit of fluorescent material and being placed above the transparent tube 3 which, in the foregoing case, is an ordinary neon tube.

It is obvious that as many tubes as are desired may be placed in the envelope so as to produce a light of desired power and color.

Furthermore, the supply transformers may be provided with devices for regulating the current

to one or the other of the tubes so as to obtain lights of different tonalities.

I claim:

1. An illuminating apparatus utilizing two electric discharge tubes giving light of different colors adapted to furnish in all points of space about the apparatus and near the same a light of substantially uniform tone, comprising in combination a cylindrical envelope, a transparent discharge tube in said envelope, a diffusing discharge tube in said envelope, said diffusing tube being opaque to rays emanating from the other tube, the two tubes having their axes located in the same diametrical plane of the envelope, and a band of opaque and reflecting material positioned on the wall of the envelope, said band being of a size at least equal to that defined by the intersection with the wall of the envelope of the cone of shadow cast by the opaque tube when subjected to the luminous rays emitted by the 20 transparent tube, the diameter of the envelope being sufficiently large in order that the presence of the reflecting band will not appreciably modify the distribution of luminous intensities in the space about the envelope. 25

2. An apparatus according to claim 1, in which the opaque diffusing tube comprises a tube coated interiorly with fluorescent material.

3. An illuminating apparatus as claimed in claim 1 wherein the cylindrical envelope is dif- 30 fusing.

4. An illuminating apparatus as claimed in claim 1 wherein the cylindrical envelope is dif- 35 fusing and wherein the opaque diffusing tube comprises a tube coated interiorly with fluorescent material.

ANDRÉ CLAUDE.
